(57) **CLAIM**

The ornamental design for a water slide, as shown and described.

DESCRIPTION

FIG. 1 is a perspective view showing our new design; FIG. 2 is a top plan view thereof;

FIG. 3 is a front elevation view thereof;

FIG. 4 is a left side elevation view thereof;

FIG. 5 is a rear elevation view thereof;

FIG. 6 is a right side elevation view thereof;

FIG. 7 is a bottom plan view thereof;

FIG. 8 is a perspective view thereof;

FIG. 9 is a partial perspective view thereof;

FIG. 10 is a partial perspective view thereof;

FIG. 11 is a partial perspective view thereof; and,

FIG. 12 is a partial perspective view thereof.

The middle portion of the water slide shown in broken lines indicate indeterminate length and forms no part of the claimed design. The broken line showing the connection system on the ends of the pontoons, the air valves on the water slide and the attached water slide are included for the purpose of illustrating unclaimed subject matter and forms no part of the claimed design. The broken lines showing the end flaps at ends of the water slide, a portion of a hose at water connection end of a pontoon, and straps are included for the purpose of illustrating unclaimed subject matter and forms no part of the claimed design.

The broken lines shown form no part of the claimed design.

1 Claim, 12 Drawing Sheets
